(57) **CLAIM**

The ornamental design for a beaded fabric, as shown and described.

DESCRIPTION

FIG. 1 is a top front right side perspective view of a beaded fabric.

FIG. 2 is a front side view thereof.

FIG. 3 is a rear side view thereof.

FIG. 4 is a left side view thereof.

FIG. 5 is a right side view thereof.

FIG. 6 is a top view thereof; and,

FIG. 7 is a bottom view thereof.

The broken lines in FIGS. 1-7 define portions of the beaded fabric which form no part of the claimed design.

1 Claim, 4 Drawing Sheets
